UNITED STATES PATENT OFFICE.

JOHN W. WESTENDORF, OF BALTIMORE, MARYLAND.

WINDOW-SHADE FIXTURE.

Application filed August 23, 1926. Serial No. 130,863.

This invention relates to an improved window-shade fixture and has for some of its objects to provide a structure that may be attached to a window-frame without the use of screws or nails; which may be readily adjusted to accommodate shade-rollers of varying lengths; whose bracket-member may be used at either the right or left end of the roller and to provide a structure of sheet-metal that may be produced at low cost.

With these and other objects in view, the invention is illustrated in the accompanying drawing, wherein,

Fig. 1. shows two spaced fixtures embodying the invention with a shade and roller mounted thereon.

Fig. 2. illustrates a cross-sectional detail through the guide and bracket members showing the same as they would appear if viewed on the line 2-2 of Fig. 1.

Fig. 3. shows the guide member in end elevation.

Fig. 4. illustrates the same in top or plan view.

Fig. 5. shows a longitudinal sectional detail through the guide-member, — the section being taken on the line 5-5 of Fig. 4.

Fig. 6. illustrates the detached bracket-member in top-view.

Fig. 7. shows the bracket-member in end elevation and prior to the folding of its bearing-end merely to more clearly illustrate the structure.

Fig. 8. illustrates in end elevation that bracket-member in which the pin-bearing of the roller is engaged, and

Fig. 9. shows the same in plan or top view.

Referring to the drawing the numeral 9 designates the guide-member which is formed from a sheet-metal plate and has turned-over longitudinal guide-flanges 10, along its opposite sides and down-turned opposite ends 11. These opposite down-turned ends are corrugated in a direction at right-angles to the outer bearing face 12 of the member, and the lower end of each corrugation 13, is provided with a notch 14.

The lower edge of these corrugated ends 11, has a series of spaced inward bevels 15, on the outer side while at the inner side, and alternating with the inward-bevels said lower edge also has a series of outward bevels 16.

These alternating bevels 15-16 at the lower notched edge of the ends 11, produces a series of wedge-like cutting edges which

may readily be driven into woodwork to securely retain the guide-member in place without the aid of additional fastenings.

Between the two guide-flanges 10, and also extending longitudinally, the guide-member is provided with two parallel but spaced slits 17 while the metal of said member between said slits is pressed outwardly to form a spring leaf 18 and this leaf midway between its ends has an outward bump or projection 19, as clearly shown in Figs. 2-4 and 5 of the drawing.

Each guide-member has associated therewith a bracket-member and as the ordinary spring shade-roller usually has a squared spring-actuated shaft at one end and a pin-bearing at the opposite end, it is customary to provide bracket-members with suitable bearing-openings to receive these two different forms of roller ends.

With this in mind, I provide two forms of bracket-members 20 and 21 respectively but I will first describe the member 20 because it is designed to receive the squared end of the spring-actuated shaft.

Referring to Figs. 1-6 and 7 of the drawing, it will be seen that the bracket-member 20 has a flat base-plate 22 and a right-angle end 23.

The base-plate 22 is of a width that will fit on or against the outer face 12 of the guide member between the two guide-flanges 10 and this base-plate is provided with a series of spaced recesses 24, on its under side which form correspondingly-shaped projections 25 on the outer side of the plate. These recesses 24, are arranged in a row so as to be in alignment with the single projection 19, on the spring leaf 18 of the guide-member beneath them, and as the bracket plate is moved in the guide-plate the spring leaf 18 will yield as the projection 19 rubs against the under side of the base plate so that the said projection will snap into the successive depressions as the base-plate is moved.

Obviously the entering of the projection 19, in any one of the depressions 24, will lock the two plates together and the spring leaf 18 will at the same time press the bracket-plate 22 outwardly against the guide-flanges 10 so as to keep the projection 19 entered in the depression 24.

The right-angle end 23 of the bracket-member 20, extends outwardly from the base-plate 22 and preferably has a back-turned end 26

which lies in parallel relation to the end 23 but is spaced therefrom, as shown in Fig. 6, of the drawing.

The end portion 23 of this bracket-member has an outwardly-pressed boss 27 with a squared slot 28 at the center thereof which slot extends outwardly through the boss to one edge 29 of the bracket-member so as to form a socket for the squared end 30 of the 10 roller shaft.

The back-turned end 26 of this same bracket-member also has a boss 31 and this latter boss is provided with a squared slot 32 which opens at the opposite edge 33 of the 15 bracket-member.

It will thus be understood that the two slots 28 and 31 open at opposite edges of the bracket-member and that when the end 26 is folded at the side of the end 23 these two 20 slots will be located in the same vertical plane so that if the bracket-member should be reversed in the guide-member one or the other of the squared sockets 28 or 32 may be utilized to engage the squared end of the roller shaft.

This capability of reversal of the bracket-member in the guide-member materially increases the range of adjustment and enables a very wide shade or a narrow shade to be used without disturbing the fixed guide-member.

For the purpose of rigidity and stiffness, I provide the bracket ends 23-26 with a central stiffening rib 34.

The bracket-member 21, has the same form 35 of base plate 22, as the member 20 and also has the same arrangement of bottom recesses 24 and outward projections 25,—the only difference being that in the outwardly-extending arm 35 said end has a complete circular 40 boss 36 with a central perforation 37 to receive the pin 38 on the end of the roller.

Obviously, this bracket-member 21 may

also be reversed end for end in the guide member to give a greater range of adjustment.

A stiffening rib 39 is also provided in the 45 arm 35 of the bracket-member for reinforcing the same.

Both bracket-members 20 and 21 are provided with notches 40 at the base of the arms or ends 23-35 and adjacent to the base plate 50 22, in order that the arm may clear the guide-lugs 10 on the guide-member.

The operation is believed to be obvious without further explanation thereof.

Having described my invention, I claim:— 55

1. In a window-shade fixture the combination with a guide-member having out-turned horizontal top and bottom guide-flanges and back-turned opposite ends each back-turned end of the guide-member being provided with sharpened edges for entering woodwork at right angles to the outer face of the guide-member and between said ends the guide-member having a spring-leaf extending parallel with and projecting outwardly between the horizontal top and bottom guide-flanges, of a bracket-member slidably engaging the flanges of the guide member and itself engaged by the said spring leaf.

2. In a window-shade fixture the combination with a guide-member having inturned guide-flanges along its opposite edges and between said flanges said member being provided with a longitudinally-extending spring-leaf which projects outwardly, of a 70 bracket-member slidable in the guide-member between said inturned guide-flanges and over the outer side of the spring leaf and means coacting between the outwardly-projecting spring leaf and the bracket-member 80 to lock the latter against longitudinal movement between the guide-flanges.

In testimony whereof I affix my signature.
JOHN WM. WESTENDORF.
